UNITED STATES PATENT OFFICE.

EDWARD J. VRAALSTAD, OF BUFFALO, NEW YORK, ASSIGNOR OF ONE-HALF TO BUFFALO PITTS COMPANY, OF BUFFALO, NEW YORK, A CORPORATION OF NEW YORK.

GRAIN-CONVEYER.

No. 875,225.

Specification of Letters Patent.

Patented Dec. 31, 1907.

Application filed February 19, 1907. Serial No. 358,271.

To all whom it may concern:

Be it known that I, EDWARD J. VRAALSTAD, of Buffalo, in the county of Erie and State of New York, have invented certain new and useful Improvements in Grain-Conveyers; and I do hereby declare the following to be a full, clear, and exact description of the invention, such as will enable others skilled in the art to which it appertains to make and use the same.

This invention relates to that class of cross conveyers disclosed by Letters Patent No. 827,049, issued to me July 24, 1906, and which is characterized by the fact that the screw may be rotated in either direction while the operating shaft revolves continuously in one direction. In the particular machine shown in that patent the grain was discharged direct into the conveyer casing at one end above one of the outlets, and it was necessary, in consequence, to close such outlet when the grain was to be delivered from the other end of the casing.

The primary object of my present invention is to avoid the necessity of having to close either outlet, and hence simplify the construction and operation of the conveyer.

A further object is to avoid the use of all locks for holding the mechanism in place, the pressure of the grain so acting on the screw as to render the use of such locks unnecessary.

The invention will be hereinafter fully set forth and particularly pointed out in the claims.

In the accompanying drawings, Figure 1 is a view in perspective. Fig. 2 is a horizontal longitudinal sectional view, with parts broken away. Fig. 3 is an end view with a part omitted. Fig. 4 is a plan view partly in section. Figs. 5 and 6 are, respectively, cross sectional views on lines 5-5, and 6-6, Fig. 4.

Referring to the drawings, 1 designates the inclosing casing, which at opposite ends has delivery outlets 2 and 3. Extended centrally through this casing is the operating shaft 4 which is designed to be constantly rotated in one direction, power being applied, preferably at 5, from any suitable source. The screw 6, as pointed out in my before noted patent, embodies a tubular spindle mounted on shaft 4 upon which it is capable of being moved longitudinally to engage with a collar 7 fast on said shaft, or

at its other end, with a hub or sleeve 8 of a transmission or reversing gearing 9. When the screw is actuated by the latter it will revolve in the direction opposite to that in which it is revolved when in engagement with collar 7.

Shifting handle 10 is slidable on a rod 12 on the exterior of the casing, to effect the movements of an arm 13, the forked end of which fits between flanges of the screw 6 spindle, such arm being passed through a slot in the casing and slidable on rod 12. Suitable lugs 14 are provided as bearings for the latter. It is not necessary to employ locks for retaining the screw in either of its two positions, the pressure of the grain being sufficient for this purpose.

15 designates a second screw conveyer by which the grain deposited from hopper 16 mounted above the casing 17 of the second screw is fed into the casing of the cross conveyer. The casing 17 opens laterally into casing 1 at a point intermediate the outlets 2 and 3, and opposite such opening the screw 15 is equipped with two arms or wings 18 by which the grain is forcibly delivered from casing 17 into casing 1.

The shaft of screw 15 carries a gear wheel 19 which meshes with a similar gear wheel 20 on shaft 4, so that the short conveyer or feeder screw is, like the operating shaft of the cross conveyer, driven constantly in one direction, the use of reversing mechanism for the driving gears being unnecessary. To change the direction of delivery of the grain by the cross conveyer, it is only necessary to shift the latter longitudinally, to place it in engagement with either of the two clutches.

From what has been said it will be seen that the grain instead of being delivered directly into the casing of the cross conveyer, is received in the casing of the feeder, and by the latter discharged into the main casing at a point intermediate the two outlets therefrom. In consequence no valve for closing either of the outlets is necessary.

I claim as my invention:

1. A conveyer comprising a rotating screw, a casing therefor having outlets at its opposite ends, means for changing the direction of rotation of the screw, a hopper, and means for feeding grain from the hopper into said casing, said means located wholly at a point intermediate said outlets.

2. A conveyer comprising a rotating screw, a casing therefor having outlets at its opposite ends, means for changing the direction of rotation of the screw, a hopper, and 5 constantly operated means for feeding grain from the hopper into said casing, said means located wholly at a point intermediate said outlets.
3. A conveyer comprising a rotating screw, a casing therefor having outlets at its opposite ends, means for changing the direction of rotation of the screw, a grain-receiving casing opening into the former casing at 10 a point intermediate said outlets, and means 15 in said grain-receiving casing for feeding grain into the first mentioned casing.
4. A conveyer comprising a rotating screw, a casing therefor having outlets at its opposite ends, means for changing the direction of rotation of the screw, a grain-receiving casing opening into the former casing intermediate said outlets; and a second screw located in said grain-receiving casing 20 for feeding grain into the first mentioned 25 casing.
5. A conveyer comprising a shaft designed to be continuously operated in one direction, a screw concentric to and operated by said shaft, means for causing said screw 30 to rotate with, or in reverse direction to, said shaft, a casing for said screw having outlets at its opposite ends, a grain-receiving casing 35
- casing opening into the former casing intermediate said outlets, and a second screw located in said grain-receiving casing and 40 operated by said shaft.
6. A conveyer comprising a shaft designed to be continuously operated in one direction, a screw concentric to and operated by said shaft, means for causing said screw 45 to rotate with, or in reverse direction to, said shaft, a casing for said screw having outlets at its opposite ends, a grain-receiving casing opening into the former casing intermediate 50 said outlets, a second screw located in said grain-receiving casing, and gearing between said second screw and the shaft of the first mentioned screw.
7. The combination with a cross-conveyer, and a casing therefor having outlets at its 55 opposite ends, of the grain-receiving casing parallel to said former casing and into which it opens at a point intermediate said outlets, a constantly-operated screw in said grain-receiving casing, and wings on said second screw for forcing the grain into the first mentioned casing.

In testimony whereof, I have signed this specification in the presence of two subscribing witnesses.

EDWARD J. VRAALSTAD.
